CLAIM

The ornamental design for a door seal, as shown and described.

DESCRIPTION

FIG. 1 is a perspective view of a door seal showing my new design;

FIG. 2 is an enlarged front elevational view thereof;

FIG. 3 is an enlarged rear elevational view thereof;

FIG. 4 is an enlarged, partial left side elevational view thereof; with a break in the center for illustration purposes so that the enlarged view may fit the page;

FIG. 5 is an enlarged, partial right side elevational view thereof;

FIG. 6 is an enlarged, partial top plan view thereof; and, FIG. 7 is an enlarged, partial bottom plan view thereof.

The broken away lines of FIGS. 4–7 are for the purpose of illustration so that the enlarged, partial views may fit the page. The broken lines defining the break for enlargement purposes form no part of the claimed design.
